PORCELAIN ART CARRYING CASE

Mollye Anne Kahn and Robert Kahn, both of 3855
Arroyo Road, Fort Worth, Tex. 76109

Filed May 14, 1974, Ser. No. 469,652

Term of patent 14 years

Int. Cl. D3—02

U.S. Cl. D87—1 R

FIG. 1 is a front perspective view of a porcelain art carrying case showing our new design in open position.

FIG. 2 is a top plan view thereof on a reduced scale.

FIG. 3 is a bottom perspective view thereof;

FIG. 4 is a front perspective view of the porcelain art carrying case shown in a closed position; and

FIG. 5 is a bottom perspective view thereof.

We claim:

The ornamental design for a porcelain art carrying case, as shown and described.
